JOHN F. WALLACE, OF BIRMINGHAM, PENNSYLVANIA.

Letters Patent No. 92,128, dated June 29, 1869.

IMPROVEMENT IN STEAM-ENGINE SLIDE-BALANCE VALVES.

The Schedule referred to in these Letters Patent and making part of the same.

To all whom it may concern:

Be it known that I, JOHN F. WALLACE, of Birmingham, in the county of Allegheny, and State of Pennsylvania, have invented a new and useful Improvement in Balance Slide-Valve; and I do hereby declare the following to be a full, clear, and exact description thereof, reference being had to the accompanying drawing, making a part of this specification, in which—

Figure 1 is a transverse vertical, and

Figure 2, a longitudinal vertical section of my improved slide-valve, the latter as formed by a plaine passing through the steam-chest parallel with the valve-stem, but a little in front of it.

Like letters of reference indicate like parts in each.

My invention relates to the construction of an improved balance slide-valve for steam-engines, in which the downward pressure exerted by the steam on the valve is relieved or balanced by an opposite upward pressure; and

The nature of it consists in making the upper part of the valve of a T-shape, and interlocking therewith a slotted box, or a box U-shaped, with inwardly-projecting edges, and attached to or forming a part of the balancing plunger, so that in operation, the T of the former will slide or roll by interposed rollers on the projecting edges of the slotted box; and

It further consists in the arrangement of the valve and plunger, so constructed, with one or more series of loose rollers, by which to convert sliding into rolling friction.

To enable others skilled in the art to make and use my invention, I will proceed to describe its construction and mode of operation.

a' represents the bottom plate of the steam-chest a of a steam-engine, having steam and exhaust-ports c, all of the usual or any known construction.

b is a slide-valve, made with a lower face, to open and close the ports c c', alternately, as it receives its throw from the stem b in either direction.

Steam is admitted into the steam-chest a by a steam-pipe from the boiler.

Ordinarily, the pressure exerted by the steam on the valve b would be so great, that either the lower face of the valve b, or its seat on the bottom plate a', or both, would speedily be worn or cut away, and at the same time there would be a considerable waste of power in giving the valve the requisite throw. I hence make the upper part of the valve b of a T-shape, as shown at n.

On the lower part of the plunger f, I make a box, d, slotted in its lower side, so as to admit therein the neck of the T-part n of the valve b, and the cavity of the box at least large enough to admit the head of the T, as shown in fig. 1, d' being the inwardly-projecting edges on either side of the slot-box referred to. The box d and valve b should be of about the same length.

Attached to the upper end of the box d is a balanc-

ing-plunger, f, preferably of cylindrical shape, which plays through a stuffing-box, g, in the upper part of the steam-chest a, the whole being enclosed by a cover, g', and all the parts properly attached and connected.

The superficial area of the cross-section of the plunger f is somewhat less than the area of the valve b, subject to the downward pressure of the steam. These relative areas may be so regulated at pleasure as to secure the end in view, which is to balance the downward pressure of the steam on the valve b, by its upward pressure on the lower end of the plunger f, but still to secure a downward pressure, sufficiently in excess of the upward pressure, to keep the valve b well to its seat.

It will be observed that while the valve b plays back and forth, the plunger f has no motion, except that produced by the upward pressure of the steam.

To reduce friction to a minimum, I interpose, between the two, one or more series of rollers, e, two or more in each series.

The under face of the head n of the T is chambered out on each side of the neck n', so as to make room for the operating of the rollers e therein. These rollers I make of such diameter, relative to the length of the stroke of the valve b, that with each stroke the rollers will make one or more complete revolutions, as near as may be; for if they each were to make a fractional part of a revolution, they would soon be worn out of a round or cylindrical shape. By the use of such rollers, in the manner described, sliding is converted into rolling friction, and of course reduced to a minimum.

The cover g' may have an interposed packing, s, and the plunger f be screwed by a nut, s', down, so that the valve may be fairly seated; or, on the other hand, the steam-chest may be made with a tight cover, as in fig. 2, and a packing-cushion, of India rubber or other like elastic compressible material, m, may be interposed between it and the plunger f. The thickness of this packing should be such that the valve may come well down on its seat, and at the same time should have sufficient elasticity to permit of the balancing-action of the plunger, as above described.

What I claim as my invention, and desire to secure by Letters Patent, is—

1. The construction, in detail, of the slide-valve, balancing-plunger, with the interposed loose rollers, all arranged substantially as described.

2. The construction and arrangement of the cover g', as shown in fig. 2, with an elastic packing, balanced plunger, slide-valve, and loose rollers, substantially as set forth.

In testimony whereof, I, the said JOHN F. WALLACE, have hereunto set my hand.

JOHN F. WALLACE.
